(57) **CLAIM**

We claim the ornamental design for the tension release garment, as shown and described.

DESCRIPTION

FIG. 1 is a first perspective view of the tension release garment of the present invention.

FIG. 2 is a second perspective view of the invention shown in FIG. 1.

FIG. 3 is a front view of the invention shown in FIG. 1.

FIG. 4 is a rear view of the invention shown in FIG. 1.

FIG. 5 is a side view of the invention shown in FIG. 1.

FIG. 6 is a top view of the invention shown in FIG. 1; and,

FIG. 7 is a bottom view of the invention shown in FIG. 1.

The ornamental design which is claimed is shown in solid lines in the drawings. Any broken lines in the drawings are for illustrative purposes only and form no part of the claimed design.
